IMPACT WRENCH

Clifford E. Fitch, Cleveland, Ohio, assignor to Chicago Pneumatic Tool Company, New York, N. Y., a corporation of New Jersey

Application October 14, 1938, Serial No. 234,884

10 Claims. (Cl. 192—30.5)

This invention relates to clutch mechanism having particular application to impact wrenches for tightening and loosening nuts, bolts and the like with a rotational hammer action.

5 An object of the invention is the delivery of powerful impacts to the anvil or driven element of the clutch, unaccompanied by excessive shocks to the driving spindle, whereby the clutch is adapted for use with electric, as well as pneumatic, motors.

10 Another object is to obviate the necessity of springs which have proved to be objectionable in prior constructions because of frequent breakage.

15 A further object is to prevent accidental engagement and scoring of the end faces of the clutch teeth as they pass each other during the interval between impacts.

20 In accordance with a feature of the invention, the rotatable hammer, or driving clutch element, is moved into engagement with the anvil by means of centrifugal weights. The weights are adapted to exert a gradually increasing axial component of pressure on the hammer as it moves 25 toward the anvil, and vice versa. The weights are arranged to revolve with the spindle at a substantially constant speed, accumulating and releasing kinetic energy as the radius of gyration of the weights lengthens and shortens, respectively. The accumulation takes place while the hammer moves toward the anvil, and the releasing or redelivery of energy from the weights to the driving spindle occurs as the hammer moves away from the anvil. In prior constructions, employing a torsion or compression spring for storing potential energy, accumulation occurs while the hammer moves away from the anvil and the stored energy is delivered to the hammer during its opposite movement. The advantage of the present invention is that the kinetic energy is accumulated at a time when the driving spindle is under a relatively light load and is transmitted back to the spindle when the load on the latter is at a maximum.

45 Other objects and features of the invention will be apparent from the description which follows.

In the accompanying drawings which illustrate one embodiment of the invention:

50 Fig. 1 is a longitudinal section of a portion of an impact wrench, parts being shown in elevation, the elements being illustrated in the position they occupy when the wrench is rotated at full speed without driving any substantial load;

55 Fig. 2 is a view similar to Fig. 1, showing the

positions of the parts when the driven member is under load, and at the instant that the hammer is released from driving engagement with the anvil, the rotary displacement of the centrifugal weights away from their Fig. 1 position not being 5 shown in order more clearly to illustrate their radial displacement;

Figs. 3 and 4 are cross sections as indicated by the arrows 3 and 4 respectively in Fig. 1;

Fig. 5 is an elevational view of the lower end 10 of the driving spindle and associated ball, the relative position of the hammer being shown in broken lines;

Fig. 6 is a longitudinal section of the hammer looking in the same direction as in Fig. 1; 15

Fig. 7 is a longitudinal section of the hammer, turned 90° away from the Fig. 6 position, as indicated by the arrows 7 in Figs. 6 and 8;

Fig. 8 is a bottom plan view of the hammer illustrating also the associated balls; 20

Fig. 9 is a development of the lower end of the driving spindle, certain surfaces of the hammer being shown in broken lines, the balls being shown in full lines, the position of the parts corresponding to Fig. 1; and 25

Fig. 10 is a development similar to Fig. 9, the position of the parts corresponding to Fig. 2.

The essential parts of the impact clutch are inclosed in a housing 12 secured by bolts 13 to a transfer plate 14 and motor casing (not shown). 30 The transfer plate supports a bearing 15 for a drive shaft 16, which is held against axial movement. A driving spindle 17 has a socket 18 at its upper or rear end which receives the drive shaft. The forward part of the spindle has a recess 19 into which fits a cylindrical projection 20 on an anvil member 21. The anvil is seated, for rotary movement, in a bushing 22 secured to the bushing 12. The anvil 21 and drive shaft 16 cooperate to secure the spindle 17 against endwise and lateral movements. The front end of the anvil is adapted to be rigidly connected to a wrench socket 23. 35

The spindle 17 drives a rotary hammer 25 which has a bore 26 fitting the spindle. The hammer has a greater mass and moment of inertia than the anvil. The front end of the hammer is provided with a plurality of circumferentially spaced jaws or teeth 27 adapted to move into and out of driving engagement with jaws 28 integral with and projecting rearwardly from the anvil 21. Preferably, there are two jaws on the hammer and anvil and each of the driving or impact surfaces thereof lies in a plane passing 50 55

through the axis of rotation, as shown in Figs. 4, 7 and 8.

The driving connection between the spindle 17 and hammer 25 comprises a pair of balls 30. The exterior surface of the spindle is provided with two pairs of cam grooves, each pair being associated with one of the balls and comprising a right-hand spiral groove 31R and a left hand spiral groove 31L. As shown in Figs. 5 and 9, the right and left hand spirals communicate with each other at their lower ends, at which point they receive the associated ball 30 when the clutch is in its normal or no-load condition. Complementary pairs of right and left hand spiral shoulders 32R and 32L respectively are formed at the rear end of a bore 33 in the hammer 25. A counterbore 34 facilitates entrance of the balls 30 into the spiral grooves 31R and 31L when the parts are assembled. The balls, spiral shoulders and spiral grooves cooperate to resolve the driving force of the spindle into a rotary component for driving the hammer 25 and an axial component tending to pull the hammer teeth 27 out of driving engagement with the anvil teeth 28.

The present invention provides a novel means for resisting the axial component of force on the hammer and of moving the hammer into re-engagement with the anvil. Two pairs of ears 35 are secured integrally, or otherwise, to the spindle 17 and they support pintles 36 on parallel axes. Each pintle provides a pivotal support for a heavy centrifugal weight 38, the weights being of equal mass and positioned on opposite sides of the spindle to prevent unbalancing forces. The weights have forwardly extending projections 39 abutting against a plate 40, which is arranged to exert axial pressure against the hammer 25 through a ball bearing arrangement 41. The centers of gravity of the weights are to the rear of the pintles.

In operation, the shaft 16 drives the spindle 17 at a substantially constant speed. Assuming that the wrench socket 23 offers no substantial resistance to rotary movement, the parts assume the position shown in Fig. 1 in which the hammer 25 is held in engagement with the anvil by the centrifugal force of the weights 38, and the balls 30 are at or near the lower ends of the helical cam grooves 31R. As the resistance to rotation increases, the axial component of the force transmitted through the balls of the hammer correspondingly increases. As long as this axial component is less than the forward pressure exerted against the hammer by the centrifugal weights, the hammer teeth 27 remain in driving engagement with the anvil teeth 28 and the hammer and anvil rotate in unison. When the nut or bolt (not shown) being driven by the socket 23 becomes seated, the resistance of the anvil 21 to further rotation increases abruptly and the spindle 17 continues to turn while the hammer is substantially locked against further rotary movement. The spindle moves relative to the hammer from the position shown in Figs. 1 and 9 to the position shown in Figs. 2 and 10 causing the hammer to be lifted out of engagement with the anvil, under the camming action of the helical grooves 31R, balls 30 and spiral shoulders 32R. As the hammer 25 moves rearwardly, the centrifugal weights 38 are retracted or pushed toward the center of rotation as will be seen by a comparison between Figs. 1 and 2. Upon disestablishment of the driving connection between the teeth 27 and 28, the hammer is re-

leased for rotary movement and immediately begins to accelerate, starting from a condition in which the hammer is substantially at rest and continuing until the instantaneous speed of the hammer becomes considerably greater than the speed of the driving spindle 17. During the acceleration period the hammer is driven by the spindle through the balls 30 and overtakes the speed of the spindle due to the action of the centrifugal weights in forcing the hammer forward in cooperation with the helical cam and ball arrangement.

The present invention compares favorably with prior impact wrenches employing a compression spring for accumulating energy while the hammer moves rearward and accelerating the hammer during its forward movement by virtue of such stored energy. In such prior devices, the axial pressure on the hammer by the spring accumulator increases sharply as the hammer moves away from the anvil. In the illustrative embodiment of the present invention, the axial pressure on the hammer does not vary through such wide limits and decreases as the hammer moves rearward. An advantage of minimizing the axial pressure when the hammer is in the Fig. 2 position is that it prevents scoring of the end faces of the clutch teeth 27 and 28 as they pass over each other.

Another advantage of the present invention is that it delivers a powerful blow to the anvil with relatively little shock on the continuously rotating spindle 17 and the gears (not shown) through which the spindle is driven. Neither the hammer 25 nor the weights 38 accumulate energy while the hammer is moving away from the anvil. The centrifugal weights 38 upon being retracted, shorten their radius of gyration, thereby releasing energy to the spindle while the clutch teeth are in engagement and the hammer moves rearward. The shock transmitted to the spindle 17 through the balls at the instant of impact, which necessarily checks the speed of the spindle at that time, is partly offset by the fact that the decrease in the radius of gyration of the weights 38 tends to augment the speed of the spindle.

In short the invention minimizes fluctuations in the torque delivered by the spindle while the hammer is delivering powerful impacts to the anvil.

The cam driving connection and the clutch teeth are symmetrically arranged whereby the operation is substantially the same for either direction of rotation of the spindle 17. When the wrench is operated to loosen a nut or bolt, the balls 30 ride between the cam grooves 31L and cam shoulders 32L, instead of 31R and 32R as hereinbefore described.

What is claimed is:

1. A clutch mechanism comprising a continuously rotatable spindle, a clutch driving member, a clutch driven member, said clutch members having separable spaced teeth adapted to retard rotation of the driving member when the driven member encounters resistance and while the driving spindle continues to rotate, said teeth being engageable and disengageable upon movement of one member relative to the other in an axial direction, disengaging means constantly urging one of the clutch members axially toward a position in which the clutch teeth disengage and effective to interrupt the driving connection between such clutch members when the resistance to rotation becomes excessive, and means including centrifugal weights for resisting sep-

aration of the clutch members and for automatically moving them axially into re-engagement following separation.

2. An impact clutch comprising a driving spindle, coaxial driving and driven clutch members having complementary engageable teeth, a driving connection between the spindle and the driving clutch member permitting axial movement of the latter into and out of engagement with the clutch driven member, said driving connection being responsive to a predetermined resistance for automatically moving the driving member away from the driven member, centrifugal means for resisting separation of the clutch teeth and for moving them into re-engagement, said centrifugal means comprising one or more weights supported for pivotal movement toward and away from the driving spindle, said weight having an abutment positioned to move the clutch driving member axially toward re-engaging position as the weight moves away from the spindle.

3. An impact clutch comprising a driving spindle, an anvil adapted to be held against axial movement relative to the spindle, a hammer, said spindle, hammer and anvil being coaxially rotatable, said hammer and anvil having complementary teeth adapted to establish a continuous driving engagement between the hammer and anvil under certain conditions of operation and to separate automatically under other operating conditions, said anvil being adapted to encounter a variable torque resistance, means responsive to an increase in such torque resistance to effect the automatic separation aforesaid, a driving connection between said spindle and hammer permitting limited axial movement of the hammer, and means for moving the hammer automatically into re-engagement with the anvil following separation, said means comprising a plurality of centrifugal weights pivotally mounted relative to the spindle, each weight having an abutment positioned for moving the hammer toward the anvil as the weight moves away from the axis of the spindle.

4. An impact clutch comprising a continuously rotatable spindle, a rotatable impact hammer driven by said spindle and supported thereon for limited axial movement, a rotatable anvil held against axial movement relative to the spindle, said hammer and anvil being coaxial and having complementary clutch teeth operative to effect a continuous drive between the hammer and anvil when the resistance to rotation of the anvil is low, means effective when the anvil meets with relatively high resistance to move the hammer axially to declutched position, and means for exerting an axial pressure on the hammer tending to resist separation from the anvil and to move the hammer into re-engagement following such separation, said axial pressure being greater when the clutch teeth re-engage than when the clutch teeth are out of engagement, said pressure exerting means comprising one or more weights, each pivotally mounted to swing away from the axis of the spindle in response to centrifugal force, the pivot for the weight being driven by the spindle and revolving therewith.

5. An impact clutch comprising a rotatable anvil, a rotatable impact hammer for driving said anvil, complementary engageable clutch teeth carried by the hammer and anvil, said teeth being separable by axial movement of the hammer away from the anvil in response to a predetermined resistance to rotation, a continuously

rotatable spindle, driving connections between said spindle and hammer including complementary cam elements, and means for automatically moving the hammer toward re-engagement with the anvil following separation, said means cooperating with the cam elements for causing the hammer to rotate at a greater speed than the spindle as the hammer approaches the re-engaging position, said means exerting a gradually increasing axial pressure on the hammer as it moves toward the anvil, said means comprising weights mounted on pivots for swinging movement away from the axis of the spindle in response to centrifugal force and comprising driving connections for causing the pivots to be re-15 involved.

6. An impact clutch comprising a continuously rotatable spindle, an anvil, a rotatable hammer, complementary engageable and disengageable clutch teeth carried by said hammer and anvil, driving connections between said spindle and hammer comprising complementary cam elements, and centrifugal means for moving the hammer toward the anvil subsequent to the disengagement aforesaid and cooperating with said cam elements to accelerate the hammer as the latter moves toward re-engagement with the anvil, said centrifugal means comprising weights constrained to revolve in unison with the spindle but mounted for independent movement toward 30 and away from the spindle axis.

7. In an impact clutch, the combination of a rotatable hammer, a rotatable anvil, driving clutch means between said hammer and anvil capable of release to enable relative rotation 35 therebetween, cam means separate from said clutch means for effecting a relative releasing movement of said clutch means upon the imposition of an increased resistance to rotary movement of the hammer, centrifugal means for resisting separation of such clutch means, said centrifugal means cooperating with the cam means to assist in the acceleration of the hammer prior to the re-engagement aforesaid, said centrifugal means comprising weights constrained to revolve in unison with the spindle but mounted for independent movement toward 45 and away from the spindle axis.

8. An impact clutch comprising a hammer rotatable in both directions, an anvil coaxially rotatable therewith, the moment of inertia of said hammer being greater than that of the anvil, said hammer and anvil having complementary clutch teeth periodically releasable and re-engageable with a hammer action in response to relative axial movement between the hammer and anvil, driving means for said hammer, and inertia means rotatable in unison with said driving means for accumulating energy while the hammer is rotating independently of the anvil and for releasing such accumulated energy while the clutch teeth are in engagement, said inertia means comprising weights driven by the spindle in unison therewith and mounted for movement away from the spindle axis in response to centrifugal force.

9. An impact clutch comprising a driving spindle, an anvil adapted to be held against axial movement relative to the spindle, a hammer, said spindle, hammer and anvil being coaxially rotatable, said hammer and anvil having complementary teeth adapted to establish a continuous driving engagement between the hammer and anvil under certain conditions of operation and to separate automatically under other operating 75

conditions, a driving connection between said spindle and hammer permitting limited axial movement of the hammer, and means for moving the hammer automatically into re-engagement with the anvil following separation, said means comprising a plurality of centrifugal weights pivotally mounted relative to the spindle, each weight having an abutment positioned for movement in a direction generally parallel to the spindle axis and toward the hammer when the radius of gyration of the weight is lengthening, and an anti-friction thrust bearing interposed between said abutments and the hammer, said thrust bearing transmitting axial movement from the hammer to the weight abutments and vice versa.

10. A rotary impact tool comprising a continuously rotatable spindle; a rotatable anvil; an intermediate driving member arranged to cause 15 delivery of rotational hammer blows to the anvil

and thereby being subjected to shocks; and a driving connection between the spindle and intermediate member constructed and arranged to relieve the spindle of a part of such shocks, said driving connection comprising complementary 5 cam means carried by the spindle and intermediate member respectively and arranged to guide the intermediate member for limited movement relative to the spindle in a helical direction, and pressure means urging the intermediate member 10 axially relative to the driving spindle to cooperate with the cam means in the transmission of torque therebetween, characterized in that said pressure means comprises a plurality of centrifugal weights each being arranged to swing about a 15 pivot carried by the spindle, the axis of the pivot lying in a plane perpendicular to the axis of rotation of the spindle.
